VACUUM CONTROLLED STOKER

Filed July 14, 1921

UNITED STATES PATENT OFFICE

FRANK P. ROESCH, OF CHICAGO, ILLINOIS, ASSIGNOR TO THE STANDARD STOKER COMPANY, INC., OF NEW YORK, N. Y., A CORPORATION OF DELAWARE

VACUUM-CONTROLLED STOKER

Application filed July 14, 1921. Serial No. 484,605.

My present invention relates in general to controlling devices, and more particularly to combustion regulators, and has special reference to furnaces and to the regulation of the fuel and air feed thereto.

Among the more important objects of my invention are the provision of means for automatically supplying fuel to a furnace in proportion to the demand thereon or work performed thereby; the provision of means for automatically regulating the air supply to a furnace in accordance with the work performed thereby; the provision of fuel feed controlling means responsive to the draft through a furnace; the provision in a steam boiler of fuel feed controlling means responsive to variations in the steam exhaust; the provision in a furnace of means for simultaneous regulation of the fuel feed and of the air feed, and more particularly of the simultaneous regulation of these automatically in accordance with the work done by the furnace; and the provision of a new, simplified and efficient arrangement for furnace control and one more particularly adapted for the purpose of obtaining from a furnace the maximum efficiency from the fuel consumed, and for reducing the fuel consumption to a minimum.

In the attainment of the objects referred to, together with such additional benefits and advantages as may hereinafter appear or be pointed out, I have provided a construction, one embodiment of which is illustrated in the accompanying drawings in which—

Figure 1 is a view in side elevation of a locomotive showing my invention in position;

Figure 2 is an enlarged view partly in section of a portion of my invention showing the fuel feed regulation; and

Figure 3 is a section taken on line 3—3 of Figure 1 looking in the direction of the arrows, only the right half of this section being shown.

In the diagrammatic showing of Figure 1, for purposes of convenience, I illustrate a locomotive boiler, 10, the front end, 11, thereof having the steam exhaust pipe, 12, open thereto, and in turn being open to the ex-

haust flue or locomotive smoke stack, 13, said exhaust pipe being connected to the locomotive engine 12a. As is evident, the steam issuing from the exhaust, 12, is proportionate to the work being performed by the locomotive, 10, and creates a vacuum in the boiler front end or vacuum chamber 11 which bears a direct relationship to the demand on the boiler, which necessarily governs the desired fuel consumption and air need.

For accomplishing the desired ends, I have devised a construction which I will now proceed to describe, and in which the fuel feed is made responsive to conditions such as exist in the boiler front end, 11, or in any other part of the boiler where the aforementioned or similar conditions are found.

For purposes of convenience, I have illustrated my invention as used with a mechanical stoker having the driving engine, 15, operated by a motive fluid preferably by steam supplied thereto from any desired or preferred source, although as will be obvious as this description proceeds, my invention is equally useful and applicable where an atomizer is used for supplying liquid fuel as in oil burning locomotives, as well as in other places, and for other purposes where the variation in air exhaust can be made of avail for regulation.

The motive fluid, preferably steam, is supplied to the stoker engine, 15, from a source, 15', by the pipe connection, 16, the flow of the fluid through the pipe being controlled at 17 by the valve, 18, movable in the valve casing, 19. This valve, 18, is moved in accordance with the vacuum in the front end of the boiler, 10, in the following manner, viz:

Positioned in the front end, 11, is the vacuum intake end, 20, connected by the pipe, 21, to one end of the expansion chamber, 22, a pipe, 23, leading from the other end of the chamber, 22, to one side of the diaphragm, 24, positioned intermediate the bow-shaped halves, 25, forming the diaphragm chamber, 26. This diaphragm chamber, 26, on the other side of the diaphragm, 24, is open to the atmosphere, as clearly shown at 27.

As a result of this arrangement, there will be a pressure of one atmosphere at all times

on the right side of the diaphragm, 24, whereas the pressure on the other (i.e. the left) side of the diaphragm, 24, will be that of the front end, 11, of the boiler or of such other part of the boiler as may be used for this purpose.

Secured to and centrally of the diaphragm, 24, at one of its ends is the valve operating lever, 28, passing through the opening, 27, the other end being secured to the valve, 18.

As a result of this arrangement, the diaphragm, 24, will have a constant pressure on one side (i.e. its right side) and a variable pressure on its other side (i.e. its left side) dependent upon the extent of withdrawal of steam from the boiler and its discharge into the front end, 11.

As noted previously, the discharge of steam from the exhaust, 12, will produce a substantial vacuum in the front end, 11, which in turn will result in a decrease in pressure on the left of the diaphragm, 24.

The diaphragm, 24, which is preferably made of an extensible material such as thin sheet brass will thus be concave toward the left, and the lever, 28, will be caused to move in the same direction, carrying with it the valve, 18, thus opening the passage through the pipe, 16, to a greater or less extent and admitting the motive fluid to stoking engine to cause it to feed fuel at a speed proportionate to the extent of movement of the valve, 18, which in turn is dependent upon the amount of decrease in pressure on the left of the diaphragm, 24, which in its turn is dependent upon the amount of vacuum produced in the front end by the withdrawal of steam from the boiler.

The expansion chamber, 22, serves to eliminate fluctuations or pulsations in the fluid column.

For maintaining the valve, 18, in its closed position of Figure 2, unless and until a vacuum in the front end, 11, produces a movement of the valve to the left, the valve casing, 19, is provided with the spiral spring, 30, seating at one end against the valve, 18, and at the other end against the cap, 31, threaded on the valve chamber, 19, for adjustment thereon so as to vary the action of the spring, 30. The lock-nut, 32, maintains the cap, 31, against movement. A cap, 33, is threaded on the opposite end of the valve casing, 19, to act as an abutment stop for the valve, 18.

To permit of the manual control of the fuel feeding mechanism, as may be requisite or desirable, I have provided the conduit, 16, with the by-pass, 34, around the valve chamber, 19, the manually operated auxiliary valve, 35, controlling the flow of motive power through this by-pass, 34. The automatically operated control valve may be rendered inoperative altogether through the cut-out cock, 36, provided at any suitable point to the left of the diaphragm, 24, so that the

fuel feed will be wholly manually controlled.

I have also provided an automatic regulation of the air supply for combustion purposes in the following manner. In Figure 3 I show in cross-section on the right half of the ash pit, 37, taken on the lines 3—3 of Figure 1, looking in the direction of the arrows. (As both halves of this ash pit are exactly the same, the description of the right half illustrated in Figure 3 will answer also for the left half.) The ash pit, 37, is provided with suitably positioned and dimensioned dampers, 38, which control the openings between the mud ring of the furnace or fire box of the locomotive engine 12^a and the ash pan, which openings are preferably of an area substantially equal to 15% of the total grate area.

The dampers, 38, are arcuate in shape and pivoted to swing about the axis, 39. Secured to each damper, 38, is an operating lever, 40, hinged at its free end at 41 to the lever, 42, pivoted to a fixed support at 43. The opposite end of each lever, 42, is slotted as shown at 44, the levers, 42, being arranged so as to have their slotted portions, 44, in overlapping relation as clearly shown in Figure 3.

It is desirable that the dampers, 38, be controlled automatically by the same means and in the same manner as is the fuel feeding mechanism, described above, and for this purpose, the pipe, 45, leads from the expansion chamber, 22, to one side of a diaphragm chamber, 46, which is in all substantial respects like the diaphragm chamber, 26, both in construction and operation.

To this end, a rod, 47, is attached to the diaphragm (not shown) in the diaphragm chamber, 46, and this rod, 47, has a portion, 48, at its lower end passing through the slots, 48, in both levers, 42.

It is obvious from what has been set forth previously, that upon the creation of a vacuum in the front end due to the withdrawal of steam from the boiler, such vacuum or decrease in pressure will make itself felt on one side of the diaphragm in the chamber, 46, to cause the rod, 47, to move upwardly, moving the lever, 42, clockwise, pulling the rod, 40, generally to the left in Figure 3, thus opening the damper to an extent dependent upon the decrease of the pressure.

Upon viewing Figure 1, it will be seen that the parts of the construction are so positioned as to bring the manual controls within reach in the engineer's cab.

Having thus described my invention and illustrated its use, what I claim as new and desire to secure by Letters Patents is—

1. In a device of the character described, in combination, a locomotive boiler and furnace, means for feeding fuel thereto, a steam engine, operated by steam from said boiler, and means for actuating said fuel feed means,

said actuating means being directly responsive to variations in the production of the draft through the furnace created by exhaust steam from said engine irrespective of the pressure in the boiler.

5 2. The combination with a locomotive engine and its steam boiler and fire box, said boiler having an exhaust device, of an engine for a mechanical stoker for said locomotive 10 engine, connections between the stoker engine and the boiler whereby the stoker engine is operated by steam from the boiler, and means connecting said connections with said exhaust device, said means comprising devices responsive to variations in the exhaust 15 for controlling the passage of steam through said connections between the steam boiler and the stoker engine.

20 3. In a device of the character described, in combination, with a fluid pressure operated locomotive, of automatically operative fuel feeding means, and means connected to said fuel feeding means and including a pressure sensitive element responsive to variations in the load imposed upon the locomotive 25 in operation in proportion to the vacuum produced by the exhaust steam from the engine thereof for varying the operation of said fuel feeding means.

30 4. In a device of the character described, in combination, a steam boiler, an engine, a furnace therefor and a damper for admitting air to the furnace, and means responsive to the vacuum produced by the exhaust of steam 35 from the engine and a connection from said means to and for controlling the position of the damper.

40 5. The combination with a locomotive engine and its steam boiler and fire box, said boiler having an exhaust device, of an engine for a mechanical stoker for said locomotive engine, connections between the stoker engine and the boiler whereby the stoker engine is operated by steam from the boiler, means 45 connecting said connections with said exhaust device, said means comprising devices responsive to variations in the exhaust for controlling the passage of steam through said connections between the steam boiler and the stoker engine, and additional devices connected to said exhaust device for controlling the air supply to said steam boiler.

50 6. The combination with an engine, and a source of power therefor, of a vacuum chamber 55 connected with said source of power and the pressure wherein varies with the speed of the engine, and means responsive to the exhaust of the engine for controlling the supply of power to the engine variable with the 60 variation in pressure in said chamber.

65 7. The combination with a steam boiler, and a steam engine, of a vacuum chamber, means for increasing and decreasing the relative vacuum therein by means of exhaust steam from the engine, a pressure-sensitive

device, a fuel control device, and operative connections between said pressure-sensitive device, said vacuum chamber, and said fuel control device whereby as the sub-normal pressure in said chamber decreases the fuel 70 feed is increased and as the sub-normal pressure rises the fuel feed is decreased, thereby regulating the fuel feed in accordance with the rate of exhaust from said engine controlled by the load and speed of said engine. 75

8. In a device of the character described, in combination, a steam boiler having an exhaust flue, a steam engine operated by steam from said boiler and exhausting into said flue, and means operated by the vacuum 80 created by said exhausting steam from the engine in said flue for controlling the fuel supply to the firebox of said boiler.

9. In a device of the character described, in combination, a steam boiler having an exhaust flue, a steam engine operated by steam from said boiler and exhausting into said flue, and means operated by the vacuum 85 created by said exhausting steam from the engine to said flue for controlling the air 90 supply to the firebox of said boiler.

10. In a device of the character described, in combination, a steam boiler having an exhaust flue, a steam engine operated by steam from said boiler and exhausting into 95 said flue, and means operated by the vacuum created by said exhausting steam from the engine in said flue for controlling the fuel and air supply to the firebox of said boiler.

11. In a device of the character described, in combination, a steam engine, a furnace having an exhaust flue, said steam engine delivering exhaust steam into said exhaust flue in accordance with its speed and load, means for controlling the combustion in said furnace, and means for actuating said controlling means including an element responsive to variations in the vacuum thus created in said exhaust flue in accordance with work performed by said engine. 100

12. In a device of the character described, in combination, a steam engine, a furnace having an exhaust flue, said steam engine delivering exhaust steam into said exhaust flue in accordance with its speed and load, fluid pressure operated means for controlling the combustion in said furnace including an element responsive to variations in the vacuum thus created in said exhaust flue in accordance with work performed by said engine, and means for eliminating undue fluctuations in said fluid pressure operated means. 115

13. In a device of the character described, in combination, a steam engine, a furnace having an exhaust flue, said steam engine delivering exhaust steam into said exhaust flue in accordance with its speed and load, fluid pressure operated means for controlling the combustion in said furnace, means for 120 125 130

actuating said combustion controlling means including an element responsive to variations in the vacuum thus created in said exhaust flue in accordance with work performed by said engine, and means interposed between the exhaust flue and said actuating means for eliminating undue fluctuations of the fluid pressure operated means.

14. In a device of the character described, 10 in combination, a steam engine, a furnace having an exhaust flue, said steam engine delivering exhaust steam into said exhaust flue in accordance with its speed and load, fluid pressure operated means for controlling the 15 combustion in said furnace, means for actuating said combustion controlling means including an element responsive to variations in the vacuum thus created in said exhaust flue in accordance with work performed by said engine, and means including 20 an expansion chamber between said exhaust flue and said fluid pressure operated means for eliminating undue fluctuations of the latter.
15. The combination with a locomotive engine and its steam boiler and fire box, said boiler having an exhaust device, of an engine 25 for a mechanical stoker for said locomotive engine, connections between the stoker engine and the boiler whereby the stoker engine is operated by steam from the boiler, a valve in said connections, and means connecting said exhaust device with said valve for automatically varying the position of said valve in correspondence with variations in the exhaust steam from the boiler.

In testimony whereof I have hereunto signed my name.

FRANK P. ROESCH.
